COMBINED HAIR SHAPER AND COMB

Arthur J. Macon, 9617 Cambury Drive, Santee, Calif.

Filed Feb. 25, 1963, Ser. No. 73,706

Term of patent 14 years

(Cl. D86—8)

Fig. 1

Fig. 2

Fig. 3

Fig. 4

Fig. 5

Fig. 6

I claim:

The ornamental design for a combined hair shaper and comb, as shown.
